UNITED STATES PATENT OFFICE.

WILLIAM Z. RANSOM, OF ST. JOSEPH, MISSOURI.

ELEVATOR.

SPECIFICATION forming part of Letters Patent No. 375,385, dated December 27, 1887.

Application filed September 17, 1887. Serial No. 249,999. (No model.)

To all whom it may concern:

Be it known that I, WILLIAM Z. RANSOM, a citizen of the United States, residing at St. Joseph, in the county of Buchanan and State 5 of Missouri, have invented a new and useful Improvement in Elevators, of which the following is a specification.

My invention relates to improvements in warehouse and passenger elevators, in which, 10 as the elevator passes up or down from floor to floor, that gate or door which is at the platform of the elevator will alone be opened.

The object of my improvement is to provide a guard that will prevent persons through carelessness or misapprehension stepping into the 15 open hatchway.

I attain my objects by the mechanism illustrated in the accompanying drawings, in which —

20 Figures 1, 2, and 3 are front views of the elevator. Fig. 4 is a side view of the elevator, showing pulley P, cord C, pulleys E and F, and drop or balance weight W. Fig. 5 shows inside of one of the main guide-posts of the elevator and cog-wheel B. Fig. 6 is a view of a rack. Fig. 7 shows a rack bolted to guide-post of car, both front and rear, forming a cogged flange operating on cog-wheel B when ascending or descending; Fig. 8, a top view showing ground 25 plan of elevator. Fig. 9 shows cog-wheel B, shaft D, and pulley P, all revolving together when racks N T operate on cog-wheel B.

Similar letters refer to similar parts throughout the several views.

35 A A are the main guide-posts of elevator shaft, extending from bottom to top of building. H H are the corner-posts; M M, guide-posts of elevator cage or platform; B, the cog-wheel keyed on shaft D and gained into and 40 flush with inside of main guide-posts A A, as shown in Figs. 1, 2, 3, 5, and 9; P, large pulley keyed on shaft D and running on the outside of main guide-posts A A, winding and unwinding cord C; C, cord attached to pulley P, running over small pulley E on the outside of corner-post H and over small pulley F on front side of corner-post H, attached to gate or bar G and opening or closing gate G.

45 G, Fig. 1, shows gate closed. In Fig. 2 it 50 shows position of gate when guide-posts M M, Figs. 1, 2, 3, and 7, are in motion, and in Fig.

3 it shows the position of the gate when open with cord C wound once around pulley P.

D, as shown in Fig. 9, is the shaft passing through main guide-posts A A, connecting 55 pulley P with cog-wheel B, all revolving together, as shown in Fig. 5; W, a drop-weight attached by swivel to pulley P, for the purpose of taking the slack of cord C and holding pulley P in position; also, with cog-wheel B in 60 position to gear into racks N or T as guide-posts M M move up or down; N, a cogged rack bolted onto guide-posts M M at the lower end and rear edge of guide-posts M M; T, a cogged rack bolted on the front edge and top end of 65 guide-posts M M far enough above the top end of rack N for weight W to bring pulley P and cog-wheel B into position ready for rack N to gear into cog-wheel B when the platform guide-posts M M are in motion. Racks N and T, operating alternately upon opposite sides of cog-wheel B, open and close the gate G. Starting 70 at the first floor of elevator, the gate G opens, rack T above the cog-wheel passing upward, rack N closes the gate G on the first floor; rack 75 T opens the gate G on the second floor; rack N, following, closes the gate at second floor, and, passing on, rack T opens the gate G at third floor. Returning, the order is reversed, rack T closing the gate at third floor; rack N opens 80 the gate at second floor; rack T, following, closes the gate at second floor, and rack N opens the gate at the first floor as it started, leaving all gates closed except the gate where the platform is. That will always be open.

85 No matter how many stories high the building may be, racks N and T are needed only once, being attached to the platform of the elevator; but the balance of the machinery must be duplicated for each story of the building. 90

The foregoing combination forms an automatic machine, which puts itself in gear when approaching the floor above or below. When the door or gate is opened, where desired, it ungears itself and is at rest. When leaving a 95 door, either in ascending or descending, it gears itself for closing the door or gate and immediately closes the door or gate, and by the time the door or gate is closed it is ungeared, and the machinery is at rest until near the next 100 floor, when the foregoing operation is repeated.

What I claim as my invention, and desire to

secure by Letters Patent of the United States,
is—

1. The combination of an elevator cage or platform provided with racks on opposite sides of one of its posts, a pinion mounted on a shaft passing through a guide-post and adapted to alternately engage said racks, a weighted pulley on the opposite end of said shaft, the hatchway-gate, and a flexible connection between said pulley and the hatchway-gate, substantially as described.

2. The combination, in a warehouse or passenger elevator, of gate G, cog-wheel B, shaft D, pulleys P, E, and F, cord C, drop or balance weight W, cogged racks N and T, ¹⁵ main guide-posts A A, and cage or platform guide-posts M M, all substantially as set forth and described.

WILLIAM Z. RANSOM.
